UNITED STATES PATENT OFFICE

2,405,358

METAL WAGON BODY

William D. Johnson, Chicago, Ill.

Application June 6, 1945, Serial No. 597,788

7 Claims. (Cl. 296—15)

1

This invention relates to metal wagon bodies and its principal object is to provide a metal wagon body composed of sheets and strips of light gauge sheet metal, secured together in such a manner as to provide an extremely strong, substantial, yet comparatively light body, the members of which can be readily assembled and secured together.

Another object is to provide a truss like floor, capable of sustaining heavy loads, together with upright gussets or braces for bracing the side walls of the body.

Another object is to provide a floor, held under tension, whereby the same may be kept from sagging under the weight of the load.

Another object is to provide a novel connection between the floor and the side walls, whereby a truss like effect is obtained.

With these and other objects and advantages in view, this invention consists in the several novel features of construction, arrangement and combination of parts hereinafter fully set forth and more particularly defined in the appended claims.

The invention is clearly illustrated in the drawings accompanying this specification, in which:

Fig. 1 is a plan of a metal wagon body, embodying a simple form of the present invention;

Fig. 2 is a side elevation thereof with a part broken out;

Fig. 3 is an end elevation of the body;

Fig. 4 is a vertical cross section taken on the line 4—4 of Fig. 2;

Fig. 5 is a detail fragmental cross section taken on the line 5—5 of Fig. 2, and

Fig. 6 is a detail horizontal section taken on the line 6—6 of Fig. 2.

Referring to said drawings which are merely illustrative of one embodiment of the invention, the reference character 10 designates cross sills, which may be made of wood or metal channels.

Bolted to the cross sills are longitudinally extending, channel shaped, sills 11. Desirably angle shaped brackets 12 are spot welded to the sides of the longitudinal sills 11, and bolts 13 extend through the horizontal flanges of the brackets and through the cross sills 10, and have nuts on the lower ends that bear against the underside of the longitudinal sills. The longitudinal sills are formed with outwardly directed longitudinal flanges 14 at their upper edges which are spot welded to the sheet metal floor 15 as will be presently explained.

Adjacent the ends of the cross sills are angle

2

shaped plates 16, also provided with horizontal flanges for supporting the floor.

The floor may comprise a single sheet of light gauge metal, bent up at the side edges to form upright U bends 17 of which the webs 18 extend down to the sills 10 and are formed with horizontally extending flanges 20 that rest upon the sills and are bolted thereto by bolts and nuts 19, thereby placing the entire floor under tension.

10 Reinforcement strips 21 may be interposed between the sills 18 and extend underneath the channel shaped members 11 and the flanges 20 and rest on the bolsters, (not shown) which strips are bent upward at their ends to provide upright members 22, that are disposed outwardly of the U bends 17.

Between the depending portions 18 and upright members 22 of the reinforcement strips are the sheet metal side walls 23 of the body which 20 rise above the U bends and extend down to the upper edges of the cross sills where they are bent upward as at 24 to form U bends that act to stiffen the wagon body.

The side walls 23 are bolted to the upright 25 bends 17 of the floor and to the upright members 22 of the reinforcement strips 21 by bolts and nuts 25, and the side walls are also bolted to the angle plates 16 and upright members 18 and 22 by bolts and nuts 26.

30 The side walls 23 of the body extend vertically for a portion of their height, and then are bent as at 28 to slope outwardly as at 29, and at 27 they are bent to stand upright as at 30. At their upper edge portions, the side walls are bent outward horizontally to provide flanges 31, the edge portions of which are bent downward as at 32

35 and connected to the side walls by obliquely slanting longitudinally extending strips 33, spot welded or otherwise secured to the flanges 32 and to the 40 side walls, thereby providing tubular rails that reinforce and stiffen the top edges of the side walls.

The ends of the body are closed by end walls 34 which conform to the contour of the cross section of the body and extend upward from the floor to the top edges of the side walls. The lower edge portions of the end walls may be flanged inwardly as at 35 and bolted to the floor by bolts and nuts 36, or otherwise secured to the floor as desired. The upper edges of the end walls are flanged inwardly as at 37 and then bent downwardly as at 38 to provide rails at the top of the end walls for reinforcing and stiffening the same. The rear end wall may be provided 55 with an end gate (not shown) as is customary.

For reinforcing and stiffening the side walls, vertical metal braces or gussets 39 are provided on the outer sides of the side walls. The inner edges of the braces or gussets conform to the contour of the side walls and are welded thereto. The outer edges of the braces or gussets slope outwardly from the ends of the cross sills for a considerable portion of their height and from a point approximately opposite the bends 27 of the side walls, the outer edges of the braces or gussets extend upright to the tubular rails at the upper edges of the side walls.

The outer edge portions of the braces or gussets are bent at right angles to the main webs of the braces or gussets to provide flanges 40, and the edge portions of the flanges are bent at right angles thereto to provide webs or ribs 41 that extend parallel with the main webs of the braces. The lower edge portions of the main webs of the braces may be bent into horizontal flanges 42 that are bolted to the cross sills by bolts and nuts 43. The construction just described provides very substantial and rigid braces or gussets reinforced and stiffened at their outer edges.

Similar braces or gussets 44 are applied at the front and rear corners of the body and are welded thereto as well as to the side walls, thereby providing very substantial reinforced corners for the body.

As a preference the corners of the body are reinforced and the side walls and end walls are tied together by upright angle irons 45 welded to the end walls and connected to the side walls by bolts and nuts 46.

When the bolts 13 and 19 are tightened up, the entire floor is placed under tension and the channel shaped sills 11 and angle bars 16 together with the floor sheets 15 provide a trussed floor capable of carrying heavier loads than the ordinary wagon floors.

Having thus described my invention, it is obvious that various immaterial modifications may be made in the same without departing from the spirit of my invention; hence, I do not wish to be understood as limiting myself to the exact form, construction, arrangement and combination of the parts herein shown and described or uses mentioned.

What I claim as new and desire to secure by Letters Patent is:

1. In a metal wagon body, the combination of a plurality of cross sills, a plurality of channel shaped longitudinally extending metal sills resting on said cross sills and bolted thereto, a sheet metal floor resting upon and welded to said channel shaped longitudinal sills, each side edge portion of said floor sheet being bent vertically up into inverted U shape with one of the webs of each U bend extending down to the cross sills and bent thereat into an inwardly extending flange bolted to the cross sills.

2. In a metal wagon body, the combination of a plurality of cross sills, a plurality of channel shaped longitudinally extending metal sills resting on said cross sills and bolted thereto, a sheet metal floor resting upon and welded to said channel shaped longitudinal sills, each side edge portion of said floor sheet being bent up vertically into inverted U shape with one of the webs of the U bend extending down to the cross sills and bent thereat into an inwardly extending flange bolted to the cross sills, metal side walls bolted to said U bends of the floor sheet and extending upright therefrom for a portion of their height and then sloping upward and ter-

minating in upright portions formed with tubular rails along their upper edges.

3. In a metal wagon body, the combination of a plurality of cross sills, a plurality of channel shaped longitudinally extending metal sills resting on said cross sills and bolted thereto, a sheet metal floor resting upon and welded to said channel shaped longitudinal sills, each side edge portion of said floor sheet being bent up vertically into inverted U shape with one of the webs of the U bend extending down to the cross sills and bent thereat into an inwardly extending flange bolted to the cross sills, metal side walls bolted to said U bends of the floor sheet and extending upright therefrom for a portion of their height and then sloping upward and terminating in upright portions formed with tubular rails along their upper edges, the lower edge portions of the side walls projecting below the floor to the cross sills and bent upward thereat to provide U shaped portions bolted to the U bends of the floor sheet.

4. In a metal wagon body, the combination of a plurality of cross sills, a plurality of channel shaped longitudinally extending metal sills resting on said cross sills and bolted thereto, a sheet metal floor resting upon and welded to said channel shaped longitudinal sills, each side edge portion of said floor sheet being bent up vertically into inverted U shape with one of the webs of the U bend extending down to the cross sills and bent thereat into an inwardly extending flange bolted to the cross sills, metal strips extending between the cross sills and having upright end members disposed on the outer sides of the U bends of the floor, and side walls interposed between said U bends and said upright members of the reinforcement strips and bolted thereto.

5. In a metal wagon body, the combination of a plurality of cross sills, a plurality of channel shaped longitudinally extending metal sills resting on said cross sills and bolted thereto, a sheet metal floor resting upon and welded to said channel shaped longitudinal sills, each side edge portion of said floor sheet being bent up vertically into inverted U shape with one of the webs of the U bend extending down to the cross sills and bent thereat into an inwardly extending flange bolted to the cross sills, metal side walls bolted to said U bends of the floor sheet and extending upright therefrom for a portion of their height and then sloping upward and outward and terminating in upright portions formed with tubular rails along their upper edges, and metal gussets disposed on the outer sides of the side walls and having inner edges conforming to the contour of said side walls and welded thereto, said gussets extending from the cross sills to the rails of the side walls with their outer edge portions bent at right angles to the main webs of the gussets to form flanges, the edge portions of which are bent parallel with said main web portions of the gussets.

6. In a metal wagon body, the combination of a plurality of cross sills, a plurality of channel shaped longitudinally extending metal sills resting on said cross sills and bolted thereto, a sheet metal floor resting upon and welded to said channel shaped longitudinal sills, each side edge portion of said floor sheet being bent up vertically into inverted U shape with one of the webs of the U bend extending down to the cross sills and bent thereat into an inwardly extending flange bolted to the cross sills, metal side walls bolted to said U bends of the floor sheet and extend-

ing upright therefrom for a portion of their height and then sloping upward and outward and terminating in upright portions formed with tubular rails along their upper edges, and metal gussets disposed on the outer sides of the side walls and having inner edges conforming to the contour of said side walls and welded thereto, said gussets extending from the cross sills to the rails of the side walls with their outer edge portions bent at right angles to the main webs of the gussets to form flanges, the edge portions of which are bent parallel with said main web portions of the gussets, sheet metal ends walls of substantially the same contour as

the cross section of the body, and similar gussets welded to the side and end walls at the corners.

7. In a metal wagon body, the combination of cross sills, longitudinally extending flanged metal channel shaped longitudinal sills resting upon said cross sills and bolted thereto, a metal floor sheet resting upon and welded to said longitudinal sills, said sheet being bent up at its side edges to form inverted U shaped upright portions, one leg of each U bent portion extending down below the floor sheet and being flanged at its lower edge with the flange resting upon and bolted to the cross sills.

WILLIAM D. JOHNSON.
